UNITED STATES PATENT OFFICE.

EDWIN F. JOHNSON, OF ST. PAUL, MINNESOTA.

THIMBLE-EMBOSSING MACHINE.

Application filed April 27, 1928. Serial No. 273,338.

The present invention relates to a thimble embossing mechanism.

In the manufacture of thimbles, it is frequently desired to use the thimbles as advertising novelties, and to do this it is desirable to imprint the name or trade-mark of the concern or article to be advertised around the base of the thimble. When the name is simply printed upon the thimble it is apt to chip or wear off in use, and it is, therefore, desirable to produce characters of a more permanent nature thereon.

It is the object of the present invention to make a mechanism which will emboss a character upon a thimble or similar article.

In order to attain this object, there is provided in accordance with one feature of the invention, a rotating spindle having cam actuated feed mechanism thereon to pick up a thimble from a feed mechanism and insert it into a spring chuck having a band therein with the name to be embossed upon the thimble engraved therein. The spindle is provided with rollers which roll the metal of the thimble into the engraved characters in the band so that they will appear embossed upon the periphery of the thimble upon completion of the operation.

These and other features of the invention will be more fully brought out in the following description and the accompanying drawings, wherein:

Figure 1, is a view in side elevation of a mechanism embodying the present invention, with a portion of a spring chuck housing broken away to show the interior construction thereof, the mechanism being shown in the operation of embossing a thimble.

Figure 2, is a view similar to Figure 1, showing the spindle withdrawn and the completed thimble dropping from the machine.

Figure 3, is a longitudinal, sectional view through the spindle and spring chuck, showing the device in an operative position.

Figure 4, is a view of the thimble holding chuck with a thimble about to be ejected therefrom.

Figure 5, is a sectional view on the line 5—5 of Figure 3.

Figure 6, is a view of an engraved band before being bent to a circular shape for insertion within the spring chuck; and

Figure 7, is a view in side elevation of a thimble after processing in the present mechanism.

Referring to the drawings in detail, a support frame A has a tubular sleeve 1 slidably mounted in arbors 2 and 3, said sleeve being provided with a key 4 sliding 60 in grooves, not shown in the arbors 2 and 3, to prevent rotation of said sleeve. A collar 5 is rigidly connected to said sleeve by means of a set screw 6, the sleeve being slidably actuated lengthwise of its axis by means 65 of a lug, not shown, riding in a camway 7 in a cam 8 keyed to a cam shaft 9 mounted in arbors on the rear of the machine. Within the sleeve 1 is a spindle B, rotatably mounted and provided with a pulley 10 by 70 which the spindle may be rapidly rotated as by means of a belt 11.

A feed mechanism C for feeding thimbles to the machine is supported upon an angular bracket 12 mounted on the arbor 3. This 75 feed mechanism is described in detail in a co-pending application for a thimble knurling machine filed on the same day as the present application, and, it is, therefore, not deemed necessary to describe this feeding mechanism in detail.

The detailed structure of the spindle B is shown in Figure 3. It comprises a shaft 13 rotated by means of the pulley 10. A pin 14 is screwed into the end of the shaft 85 13 to project outwardly from the end thereof. This pin has a freely movable fit within a casing 15. The casing 15 is tapered at its outer, or free end, and has embossing rolls 16 mounted therein to project slightly 90 beyond the periphery of this tapered nose portion. The tapered outer end of the pin 14 rests against the inner faces of the embossing rolls 16. These rolls are held in position within the nose of the spindle by 95 means of spring steel rings 17 and 18 which exert an outward pressure on the rolls 16.

The casing 15 in which the pin 14 rotates is provided with a flange 19 around its inner end, which flange is held in position 100

by means of a retaining ring 20 fastened to the end of the shaft, as by screws 21. Ball bearings 22 support the flanged inner end of the casing 15 to permit a free, relative rotation of the casing 15 and the pin 14 which rotates with the shaft 13. A spring supported ring 23 is held in position against the ball bearing 22, as by means of springs 24. This structure permits the pin 14 to move outwardly with respect to the casing 15, wedging the rolls 16 radially outward to perform the embossing operation. The spindle B is rotatably mounted within the sleeve 1 as by means of bearings 25 and 26.

15 A spring-jawed chuck 27 is mounted in line with the axis of rotation of the spindle B and is provided with a tapered opening 28 in the end thereof to receive a thimble 29 therein. The periphery of the chuck 27 is tapered to fit into a tapered recess in the end of a sleeve 30 which is slidably mounted in supports 31 and 32. A collar 33 is secured to the sleeve 30, as by means of a set screw 34. A stud, not shown, on the rear 25 of the collar 33 rides in a cam 35 carried by the camshaft 9. The stud riding in the cam 35 moves alternately the sleeve 30 to the left over the spring-jawed chuck 27 to close the chuck, and then to the right upon 30 the opposite actuation of said cam to release said chuck.

An ejector rod 36 is slidably mounted within the chuck 27 extending outwardly beyond the outer end of said chuck and being connected by means of a rigid cross member 37 to an actuating rod 38. The actuating rod 38 is provided with stops 39 and 40 thereon, which are engaged by a stud 41 carried by the ring 5 to actuate the ejector 40 after each withdrawal of the spindle B from the chuck 27, as will be more fully brought out later in the specification.

An annular embossing matrix band 42, which may be of spring steel with characters engraved therein, as shown in Figure 6, is sprung into position in an annular recess in the chuck 27.

The operation of the device is as follows:

50 The spindle B is rapidly rotated by means of the pulley 10 and belt 11. The camshaft is operated more slowly and as the cam 8 rotates it, co-operates with the stud on the ring 5 to carry the spindle B to the right. As the spindle B moves to the right it enters the lowermost thimble held in the feedway C and carries the thimble into the 55 spring-jawed chuck 27. As the thimble enters the chuck 27 the sleeve 30 is moved to the left by means of the cam 35, as shown 60 in Figure 1.

The tapered opening in the sleeve 30 forces the jaws of the chuck 27 radially inward forcing the steel band matrix closely about the thimble.

This action grips the thimble and stops 65 its rotation. The spindle, however, continues to rotate within the thimble, the roll 16 forcing the metal of the thimble outwardly into the matrix of the band 42.

After a predetermined interval, the cam 70 8 moves the sleeve 1 to the left, withdrawing the spindle from the thimble and leaving the thimble in the chuck 27. As the spindle is being withdrawn to the left, the cam 35 moves the sleeve 30 to the right, thereby 75 releasing the spring jaws of the chuck 27, which thereupon expand, releasing the thimble which still remains therein.

As the other sleeve 5, carrying with it the spindle B approaches its extreme leftward position, the downwardly projecting lug 41 carried by said sleeve, strikes the stop 39 and moves it to the left. This stop 39 is secured to the rod 38, which in turn is securely connected to the cross member 37. The other end of the cross member 37 is fastened to the ejector rod 36 slidably mounted in the chuck 27. The moving of the stop 39 to the left thus moves the ejector rod 36 to the left, ejecting the thimble, as 90 shown in Figure 2.

The process is repeated upon each rotation of the cams 8 and 35, the stop member 40 being engaged by the lug upon moving to the right to restore the ejector rod to normal before inserting another thimble in the 95 chuck 27.

I claim:

1. A thimble embossing mechanism, comprising a spindle having a power driven inner portion and a freely rotatable outer portion, rollers mounted in an end of said spindle to ride upon the power driven inner portion and to extend beyond the periphery of the outer portion, means having indented characters therein to receive a thimble therein, said spindle being rotatable within a thimble in said means to roll said rollers about the interior of said thimble to force the metal thereof into said indented characters to thereby emboss said characters upon said thimble.

2. A thimble embossing mechanism, comprising a power driven spindle, cam means mounted to alternately advance and retract said spindle, a supply of thimbles mounted in a feedway to be entered and carried forward one at a time upon each advance of said spindle, and expandible member having a recess therein to receive a thimble carried by said spindle upon the advance thereof, a metal band having indented characters therein mounted within said recess, the spindle rotating within said thimble when in said recess to force the metal of said thimble into said indented characters to thereby emboss said characters in reversed form upon said thimble.

3. A thimble embossing mechanism, comprising a member having a recess of a size to receive a thimble, a metal band having indented characters therein mounted within 5 said recess, a spindle mounted to rotate within a thimble held in said recess, and rolling elements carried by said spindle and rolled

about the interior of said thimble to force the metal of said thimble outwardly into the indented characters in said band to thereby emboss said characters in reversed form 10 upon said thimble.

In testimony whereof I affix my signature.
EDWIN F. JOHNSON.
